UNITED STATES PATENT OFFICE.

SIMON W. FARBER, OF BROOKLYN, NEW YORK, ASSIGNOR TO S. W. FARBER, INC., OF NEW YORK, N. Y., A CORPORATION OF NEW YORK.

DESIGN FOR A LAMP BASE.

Application filed January 17, 1929. Serial No. 29,657. Term of patent 14 years.

To all whom it may concern:

Be it known that I, SIMON W. FARBER, a citizen of the United States of America, residing at Brooklyn, in the county of Kings, city and State of New York, have invented a new, original, and ornamental Design for Lamp Base, of which the following is a specification, reference being had to the accompanying drawing, forming a part thereof.

In the drawing,

I claim:

The ornamental design for a lamp base substantially as shown.

SIMON W. FARBER.
